UNITED STATES PATENT OFFICE.

LORENZ MUTHER, OF OAK PARK, ASSIGNOR TO THE UNION SPECIAL SEWING MACHINE COMPANY, OF CHICAGO, ILLINOIS.

LOOP-RETAINER FOR SEWING-MACHINES.

SPECIFICATION forming part of Letters Patent No. 556,715, dated March 17, 1896.

Application filed July 12, 1894. Serial No. 517,345. (No model.)

To all whom it may concern:

Be it known that I, LORENZ MUTHER, a citizen of the United States, residing at Oak Park, in the county of Cook, State of Illinois, have invented certain new and useful Improvements in Sewing-Machines, of which the following is a description, reference being had to the accompanying drawings and to the letters of reference marked thereon.

10 My invention relates to an improvement in sewing-machines of the general class illustrated in Patent No. 344,493, dated June 29, 1886.

It has heretofore been proposed in machines of this character to provide the looper near its heel with a notch on the grooved inner edge to leave a shoulder to catch and hold the loop of the needle-thread as the looper moves backward, thus drawing the 20 loops of needle-thread out of the way of the needles as they again descend through the material to enter the loop of the thread carried by the looper. To prevent the loops of needle-thread held upon the looper as the latter is retracted or drawn backward, or out of the loops of said needle-thread, from being 25 drawn forward by the strain of the thread so as to get in the path of the descending needles, which are about entering the loop of the looper-thread, it has been proposed to provide the throat-plate at its under side and to 30 one side of the needle-hole with a transverse depression or groove and a finger against which the loops of the needle-thread arrive 35 and bear as the points of the needles descend between the looper and the looper-thread, the outer or free end of said finger substantially holding the said loops until the point of the looper in its backward movement comes to 40 the finger, the outer end of the finger projecting over said depression.

I have found in practice that if the finger does not bear a certain relation to the looper there is liability of skipping stitches, and this 45 necessary relation is destroyed either by deepening the hole for the looper-shank or otherwise setting the looper too low, or by forming the finger a little out of proper shape or allowing it to become sprung. It sometimes 50 happens that the fingers are not made precisely alike by the workman, and therefore

when put on the throat-plate do not project close enough to the edge of the looper and thus leave space sufficient to allow the needle-loops to run off the looper and to be cut off 55 by the needles or cause stitches to be dropped.

To avoid the above objections the present invention has been made; and it consists in providing means of adjustment for said finger whereby it can always be secured in proper 60 position with respect to the looper, as herein-after described and claimed.

My invention is illustrated in the accompanying drawings, in which—

Figure 1 shows a longitudinal section of 65 a portion of a cylinder vamping-machine to which my invention is applied, the looper being shown as just entering the needle-thread loops, the needles moving upward. Fig. 2 is an end view showing the parts while the looper 70 is being retracted and the needles descending to pass between the looper and its thread. Fig. 3 is a detail view of a curved throat-plate, showing the finger, the looper moving backward, and the thread; and Fig. 4 is a bottom plan view of a flat throat-plate provided 75 with my invention.

In the drawings, A represents a portion of the casing of a cylinder vamping-machine, and B is the throat-plate thereof, the same 80 letter also representing the flat throat-plate shown in Fig. 4.

C represents the looper having the usual notch forming a shoulder a, behind which in the extreme forward position of the looper the 85 needle-threads slip and by which they are drawn backward as the looper is retracted.

The ordinary looper-guard finger b is provided as well as the needle-guard c.

D is the needle-bar, herein shown as carrying the two needles d.

The throat-plate B has on its side nearest the heel of the looper a shallow transverse groove e, and a finger f, composed of a piece of wire or other suitable material, is attached 95 to the under side of the throat-plate by the screw g, the point of said finger lying close to one of the needles and extending partially over the depressed portion to leave a space 100 between the under side of the throat-plate and point of the finger. This finger is preferably made of wire or spring metal; but it

sometimes happens that in replacing the parts the finger will become sprung, so that when secured to the throat-plate it will not rest in proper relation to the looper, or it may be 5 that the fingers may not be all alike or that the looper on one machine may be set a little lower than on another, in which case the ordinary finger would not perform the desired function.

- 10 To enable the fingers to be interchangeable to adapt them to machines even after they have been sprung and to allow for inequalities in the setting of the looper, I provide a set-screw *h*, which passes through the throat-
15 plate and bears upon the upper side of the wire, and by tightening or loosening this screw the finger is adjusted to bring it into proper relation with the looper. The forward end of the finger is cut out on its under side, 20 as at *i*, to allow of the backward movement of the looper without danger of it striking the finger.

The operation will be easily understood from the foregoing description. In the forward movement of the looper the needles descend and the looper passes through the loops of the needle-threads and beyond the end of the finger. When the limit of its forward movement has been reached, the loops of the 25
30 needle-threads now around the looper slip into the notch thereon, and as the looper takes its

sidewise movement and goes backward the shoulder draws the threads aside until the looper has been retracted a portion of its distance, when the loops of the needle-thread 35 slip from the shoulder and move toward the point of the looper. When they reach the point of the finger, they are passed over it and held on it by the looper and between the finger and the under side of the throat-plate, 40 while the needles descend at the rear side of the looper and between it and its thread. When the looper reaches a point at or near the limit of its backward movement, it releases the needle-loops, which are then drawn 45 up into the goods over said finger.

Having thus described my invention, what I claim, and desire to secure by Letters Patent, is—

A throat-plate provided with a loop-retaining spring-finger, secured rigidly to the throat-plate, and a set-screw passing through the throat-plate and bearing on said finger whereby the same is vertically adjustable, substantially as described.

In testimony whereof I affix my signature in presence of two witnesses.

LORENZ MUTIHER.
